ABSTRACT: A switchpoint type of deflecting device for effecting the undisturbed distribution of continuously moving bodies which have been preliminarily deflected by a selecting station to different tracks or paths marked by special guide members. A distributing tongue prevents head-on collisions which would otherwise occur between a body and the stationary guide members as a result of insufficient preliminary deflection. The guide members are wedge-shaped with the pointed end serving to separate the individual paths, and are preceded by the vertically deflectable distributing or deflecting tongue, fitted at one end to the wedge-shaped end of the guide and pointed at the other end facing the selecting station, and whose top surface is doubly inclined downwards toward the pointed end and the deflection path side face. Urging of improperly deflected bodies in the proper direction, already begun by the selecting station, is furthered by the doubly-inclined top surface and spring-opposed downward movement of the tongue, and compulsorily completed by the guide. Properly deflected and undeflected bodies are not affected by the tongue.

SWITCHPOINT-TYPE DEFLECTING DEVICE

BACKGROUND OF THE INVENTION

This invention relates to a switchpoint-type of deflecting device for the undisturbed distribution of continuously moved bodies which have been deflected or redirected by a selecting station to different tracks marked by guiding means.

In cases where a plurality of closely following bodies, traveling at a high natural speed, are supposedly capable of being optionally distributed out of the continuous movement to different tracks, it is no longer practical to perform the distribution via mechanically moved switchpoints as a result of mass inertia problems, having a limited effect arising as the switchover time becomes shorter.

For this reason there is already in existence an arrangement by which an attempt is made to solve this problem in such a way that the individual bodies, by a corresponding previous magnetization are redirected from a normal track into another track, while passing through a magnetic distributing station, and finally approach a stationary guide which is characteristic of the new track. This guide which is arranged between the circular paths, is pointed, in the direction of the distributing station. To it there is partly attributed the function of a switchpoint.

In such a type of arrangement, however, there exists the danger that the bodies, when being insufficiently deflected and in spite of having a shuttle-shaped cross section, exactly hit the edge of the pointedly extending guide member which, unavoidably, would cause a considerable damage to the entire arrangement. These disadvantages can be avoided by the arrangement according to the invention.

SUMMARY OF THE INVENTION

A stationary guide member is preceded by a vertically deflectable, pointedly extending distributor tongue, with the opposite face surfaces of the two members extending at an acute angle in relation to their longitudinal expansion. The distributor tongue is inclined towards the point end, and its surface is inclined towards the longer longitudinal edge.

A practical application of this device is in mechanical printing mechanisms in which the types are arranged in a ring or rim-shaped fashion and which, out of the rotating movement, are caused to hit a fixed platen.

BRIEF DESCRIPTION OF THE DRAWINGS

With respect to employment with such a printing mechanism, the device according to the invention will now be explained in detail with reference to the following example of embodiment made in connection with FIGS. 1 to 3 of the accompanying drawing, in which:

FIG. 1 shows in a developed projection, the randomly controllable circular paths and the position of the device according to the invention in relation thereto, in a schematic representation;

FIG. 2 shows the device according to the invention in a sideview; and

FIG. 3 shows the subject matter of FIG. 2 in a topview.

DESCRIPTION OF THE PREFERRED EMBODIMENT

FIG. 1 permits recognition of the general arrangement of the inventive type of device within the scope of a printing mechanism operating on the aforementioned principle. In the course of this, the bodies 1 to be distributed, designed as shuttle-shaped type lever projections, approach the range of the distributing station 2 along the normal circular path as indicated by the dot and dash line. The previously marked or selected type lever projection, in the course of this, suffers a deflection in direction towards the path or track indicated by the dash line and, when properly deflected, will come to lie against the upper sliding surface of the schematically shown distributing tongue 3 in the course of the further operation, with the distributing tongue 3 being followed by the guide member 4 designed as a printing cam. At point P there is effected the printing. The rebounding type lever is intercepted

again via its projection 1 by the action of a cam 5, and is returned to its normal circular path.

FIGS. 2 and 3 show the device according to the invention in detail.

As the shuttle-shaped bodies 1, designed e.g. as type lever projections move into the range of the circular path in the direction as indicated by the arrow A, the deflecting device, substantially consisting of the parts 3 and 4, projects in such a way as not to have an influence upon those of the bodies 1 which either follow the normal circular path as indicated in FIG. 3 by the dot and dash line, or which have been properly deflected into the path as indicated by the dotted line.

It may also happen, however, that a body 1, owing to a faulty control, follows the path which is shown by the dash line in FIG. 3, in the course of which it would exactly meet upon the pointed end of the guide separating the two paths (tracks).

In order to avoid, in such a case, a damaging of the equipment, the deflecting device according the invention is provided. It substantially consists of the distributing tongue 3 which is arranged ahead of the stationary guide member 4, and which is mounted to a flat spring 7 which is held in position on one side, as shown in FIG. 2, and is retained thereby in the shown normal position. For the purpose of trapping transverse forces, the tongue 3 is supported in a guide 6 permitting the tongue to perform only a vertical movement in opposition to the action of the flat spring 7, which is restricted by a limiting stop 8.

The tongue 3 which, according to FIG. 3, has a pointed end, is designed at its opposite end to have a width corresponding to the guide member 4. The two oppositely lying face surfaces 3a and 4a of the parts 3 and 4 extend in a closely adjacent manner and parallel in relation to one another at an acute angle in relation to their longitudinal extension, so that there will result a wedge-shaped overlapping. From this overlapping range towards the pointed end 3c, the tongue 3 is inclined downwards, whereas the surface 3d is inclined downwards in the direction of the longer longitudinal edge 3b.

If now, in the course of the track or path as indicated by the dash line in FIG. 3, the body 1 meets in a direct line, via the point end 3c, upon the doubly inclined surface 3d of the distributing tongue 3, the latter will be pushed downwardly, on one hand, in the direction indicated by the arrow B by the action of the body 1 meeting thereupon. At the same time, however, the tongue 3 is acted upon by the pressure of the flat spring 7 and, via the surface 3d which is downwardly inclined towards the longitudinal edge 3b, exposes the body 1 to a transversely acting power component attempting to press the body 1 into the intended path (track). However, since this is only effected partly, the face sides 3a and 4a of the parts 3 and 4 are arranged at acute angles, so that the body 1, in the course of its further movement, and owing to the pressed down tongue 3, will come to lie against the face side 4a of the stationary guide member 4, by which it is deflected compulsorily into the intended path (track) in the direction as indicated by the arrow C.

If there is effected a smaller deflection of the body 1, so that the latter will not meet upon the inclined surface 3d, it will slide along the vertically standing longitudinal surface 3e and, because the guide 6 prevents the tongue 3 from giving way towards the side, is returned to the normal circular path.

Accordingly, in all of these cases it is avoided that a body 1, in the case of a faulty deflection, meets upon the pointed end of the edge 4b of guide member 4.

We claim:

1. A switchpoint type deflecting device for a distributing apparatus comprising:
a distributing station for deflecting a preselected one of a number of moving bodies from a first path toward another path;
a stationary guide member means having a wedge-shaped face for guiding said one deflected body into said other path; and

distributing means preceding said stationary guide member means including a vertically deflectable pointed tongue extension having a wedge-shaped face mated to said guide means and having a doubly inclined top surface sloping downwards towards the said pointed end and said second path.

2. A switchpoint type deflecting device according to claim 1 in which said distributing means further includes a flat spring fixed at one end and having said tongue extension mounted to the free end thereof, whereby the vertical deflection of said tongue extension is in opposition to said flat spring.

3. A switchpoint type deflecting device according to claim 2 in which said distributing means further includes a guide positioned to have said tongue extension rest therein so as to per-

mit only vertical movement of said tongue extension.

4. A switchpoint type deflecting device according to claim 3 in which said tongue extension has a longitudinal edge adjacent to said first path for maintaining the undeflected moving bodies therein.

5. A switchpoint type deflecting device according to claim 4 in which said stationary guide member has a longitudinal edge adjacent to said first path so as to further maintain the undeflected moving bodies therein.

6. A switchpoint type deflection device according to claim 5 in which said flat spring has a limit stop restricting the vertical stroke of said tongue extension.
